UNITED STATES PATENT OFFICE.

JULIUS J. LAMBERT, OF NEW YORK, N. Y., ASSIGNOR TO FRANK & LAMBERT, INC., OF NEW YORK, N. Y., A CORPORATION OF NEW YORK.

DESIGN FOR TEXTILE FABRIC.

42,872.

Specification for Design.

Patented Aug. 13, 1912.

Application filed June 26, 1912. Serial No. 706,091. Term of patent 3½ years.

To all whom it may concern:

Be it known that I, JULIUS J. LAMBERT, a citizen of the United States, and residing in the borough of Manhattan, in the county and State of New York, have invented a new, original, and ornamental Design for a Textile Fabric, of which the following is a specification, reference being had to the accompanying drawing, forming part thereof.

The figure is a plan view of a portion of textile fabric showing my new design.

I claim:

The ornamental design for a textile fabric, as shown.

JULIUS J. LAMBERT.

Witnesses:

H. T. LOOMIS,
GRACE E. YEATON.
